UNITED STATES PATENT OFFICE.

HARRIET CARTER, OF BROOKLYN, NEW YORK.

COMPOSITION OF MATTER FOR SAVING FUEL.

SPECIFICATION forming part of Letters Patent No. 497,627, dated May 16, 1893.

Application filed February 15, 1893. Serial No. 462,486. (No specimens.)

To all whom it may concern:

Be it known that I, HARRIET CARTER, of Brooklyn, in the county of Kings and State of New York, have invented a new and useful 5 Improved Composition of Matter for Saving Fuel, of which the following is a specification.

My improved composition of matter consists of the following named ingredients compounded as will be explained.

10 *Formula.*—Hard coal ashes, powdered and sifted, four quarts; hard coal, granulated, one quart; white sand, clean and dry, one quart; fire clay, dry and powdered, two quarts; fine salt, one-half pint.

15 The materials are mixed thoroughly with warm water, in sufficient quantity to form a plastic mass, then the composition is formed into balls of a convenient size for use, and these are baked so as to render them hard and dry.

20 In use, any suitable number of the prepared balls are placed on a fresh fire of coal in a stove or range, and lightly covered with coals. When the fire has burned a short time, after the introduction of the composition balls, the latter will become incandescent, and add largely to the heat of the fire,

and will preserve their form for a continued use of more than a week. When the coal fire needs renewal, the composition balls are removed, and replaced in the manner before 30 stated; they being available for service as fuel savers until they become wasted away.

It has been found in practice, that the specified form for the lumps of the composition will give the best results, as their spherical 35 form prevents friable disintegration, but they may be made in slabs, rectangular blocks, or any other preferred form, their size depending upon the dimensions of the fire chamber in which they are to be used. 40

Having thus described my improved fuel-saving composition of matter and its manner of use, I claim as new and desire to secure by Letters Patent—

The herein described composition of matter 45 for saving fuel, consisting of hard coal ashes, fine hard coal, white sand, fire clay, and fine salt, mixed with water, as is herein set forth.

HARRIET CARTER.
